UNITED STATES PATENT OFFICE.

JOHN N. HICKS, OF TULSA, OKLAHOMA, AND CHARLES A. ELLIOTT AND PRICE DUNBAR, OF BRECKENRIDGE, TEXAS; SAID DUNBAR ASSIGNOR TO SAID HICKS.

OIL WELL.

Application filed January 3, 1922, Serial No. 526,737. Renewed October 2, 1922. Serial No. 591,984.

To all whom it may concern:

Be it known that we, (1) JOHN N. HICKS, (2) CHARLES A. ELLIOTT, and (3) PRICE DUNBAR, citizens of the United States, residing at (1) Tulsa, Tulsa Co., Oklahoma, and (2, 3) Breckenridge, in the county of Stephens and State of Texas, respectively, have invented certain new and useful Improvements in Oil Wells; and we do declare the following to be a full, clear, and exact description of the invention, such as will enable others skilled in the art to which it appertains to make and use the same.

This invention relates broadly to an improved oil well, having more particular reference to an improved eduction conduit for use in connection therewith.

The primary object of the invention is to provide a novel structure by means of which fluids, preferably oil, can be effectively elevated from comparatively great depths, partially by means of natural gas, and when the latter fails to function, by compressed air or gas obtained from a suitable source above the surface of the ground.

One of the most important features and aims is to provide a novel eduction conduit for the oil permanently arranged in the well casing, together with an automatically compressed packing arranged between the casing and the conduit for preventing passage of the gas under pressure down into the well, whereby to prevent disturbance of the oil sand and to prevent water from passing downwardly through the well into the sand.

Another and an important object of the invention is to generally improve upon devices of this class by providing one of comparative simplicity and durability which is made up of a number of parts detachably connected together to permit replacements and repairs to be made, but yet preventing any of such parts from being lost when the conduit is withdrawn from the well casing.

Other objects and advantages of the invention will be apparent during the course of the following description.

In the accompanying drawings forming a part of this specification and in which like numerals are employed to designate like parts throughout the same:

Figure 1 is a central vertical sectional view through an improved oil well constructed in accordance with this invention

showing the position of parts prior to assuming their final relative positions.

Figure 2 is a view like Fig. 1, with parts in elevation, showing the position of parts when the well is ready for use.

Figure 3 is an enlarged detail sectional view of a portion of one of the details of the conduit.

Figure 4 is an enlarged horizontal section taken substantially on the plane of the line 4-4 of Fig. 1.

Figure 5 is an enlarged detail section showing the exact manner of telescopically connecting the upper and lower sections of the conduit together.

Briefly described, the improved well includes among other specific details, a well casing of conventional form which is sunk into the ground in the usual way, an eduction or liquid discharge conduit immovably arranged inside of the casing, and means for feeding fluid under pressure into the casing for elevating the oil through and discharging it from said conduit. The conduit is composed of telescopically connected sections and the upper section includes what may be conveniently termed a liquid chamber into which the oil rises as caused to do by the natural gases.

Referring to the drawings wherein the aforesaid parts are illustrated in their preferred embodiments, it will be seen that the well casing is designated by the numeral 1, this casing being constructed in any suitable way and being of a length to extend down into the ground the necessary distance. It is open at its upper end and a removable closure 2 serves to close this end.

The short down-turned end of a valved compressed air pipe 3 extends through this closure or communicates in any other way with the interior of the well casing for discharging the air or gas under pressure into the latter for accomplishing the end sought. Air, of course, is not permitted to enter the well continuously because under some circumstances, the natural gases in the ground will suffice to take the place of this compressed air. Consequently, the valve in the pipe 3 is closed at will whenever necessary or desired.

As before indicated, a novel eduction or liquid discharge conduit is immovably arranged in the well casing, that is, it is immovable until withdrawn for making re-

pairs, cleaning, etc. This conduit is composed of upper and lower sections 4 and 5 respectively which are telescopically connected with one another as indicated at 6. The upper section 4 is composed of a relatively long section of piping 7, a comparatively short length 8 detachably connected to the upper end thereof and a comparatively large tubular member or sleeve 9 connected with the upper end of said short pipe. By carefully examining this portion of the conduit it will be seen that a washer or the like 10 is arranged between the adjacent ends of the pipe sections and this constitutes a valve seat for a ball check valve 11. It may also be noted that an apertured disk-like part 12 carrying a depending stem 13 is arranged between the short length of pipe and the aforesaid sleeve and this serves to permit free passage of the liquid and provides a stop for controlling the upward movement of the ball check valve. For the sake of convenience of description, the short length of pipe and sleeve associated therewith will be termed a liquid chamber, because it is at this point that the oil from the bottom of the well is contained until displaced by the natural gases or gases under pressure. While on this chamber it is probably well to direct attention to the fact that in addition to including a ball check valve, it is provided with a number of other air controlled valves 14 which serve to permit the entrance of air from the external source 35 into the chamber for elevating the oil. It is also well to point out that the sleeve 9 is substantially of the same diameter as the internal diameter of the well casing, being of a size to provide a comparatively restricted air space between itself and the well casing. This restricted space serves to prevent an undesirable quantity of air or gas from entering the chamber. Although it is not absolutely essential, we prefer to construct the 45 sleeve as better shown in Fig. 3 and by directing attention to this figure it will be seen that the same is formed at circumferentially spaced points with recesses 15 partially closed at their outer ends by ring-nuts 16, the inner faces of which are constructed to form seats 17 for the spring-pressed valves 14. Diagonal ports 18 lead from these recesses 15 into the bore of the aforesaid sleeve and when the valves are unseated permit 55 entrance of the external gases for elevating the oil contained in the chamber. A discharge pipe 19 is connected to the upper end of the sleeve and leads to a suitable point of deposit.

60 By directing attention now to the lower section of the conduit it will be seen that this comprises an elongated nipple 20, to the lower end of which a perforated combined strainer and anchoring member 21 is detachably connected. This nipple 20 is of a

diameter to permit the aforesaid pipe 7 to telescope into the same as illustrated in Fig. 2. Directing attention again to the joint 6 which serves to connect the telescoping sections together, it will be seen that the outer coupling 22 constitutes a stop which functions in a manner to be hereinafter set forth.

It is yet to be mentioned that an elongated tubular flexible packing 23 surrounds the aforesaid pipe 7 and that this pipe is formed with external threads 24 which bite into the packing to prevent slippage of the latter. Washers 25 surround the pipe sections 7 above and below the packing and the lower washer prevents direct contact of the packing with the metal coupling to insure uniform compression of the packing.

Assuming that the well casing is sunk in the ground and the fluid conduits and parts thereof are in the approximate position disclosed in Fig. 1, it will be seen that as soon as the anchor 21 strikes the bottom of the hole, the lower section will become stationary. However, the upper section 4 will drop still further and the lower end of the pipe 7 will telescope into the nipple 20 so that the parts will take the position shown in Figure 2. It therefore follows that the packing 23 receives the direct weight of the pipes and the parts above it. Consequently, it is longitudinally compressed and its periphery is forced into tight contact with the inner wall of the well casing, thereby providing an extremely effective fluid-tight joint.

In operation, the oil enters the conduit through the perforations in the strainer 21 and passes upwardly, as caused to do by the natural gases into the aforesaid chamber. It is held in this chamber by a check valve and is forced from the latter by the natural gases and in cases where the latter fail to function, by means of an artificial gas or fluid under pressure introduced into the well casing through the valved pipe 3. It is obvious that the gas in this pipe passes through the restricted space between the sleeve 9 and the inner wall of the well casing and forces the valves 14 inwardly and thereby gains entrance into the chamber. Consequently, as it forces downwardly upon the surface of the oil in the chamber, the oil is displaced and elevated through the pipe 19 and carried to the desired point. It will therefore be seen that a continuous flow of oil is brought about. The fluid under pressure passing from the external source is not necessary under all circumstances and can therefore be cut off when not desired. However, when the pressure of the natural gases in the well is insufficient to properly function for elevating the oil, the artificial gas is brought into play.

By carefully considering the description in connection with the drawings, persons

familiar with devices of this class will doubtless be able to obtain a clear understanding of the invention. Therefore, a more lengthy and detailed description is deemed unnecessary.

Since probably the best results may be obtained with the construction and arrangement herein shown and described, this is taken as the preferred embodiment of the invention. However, we wish it to be understood that minor changes coming within the scope of the invention as claimed may be resorted to if desired.

We claim:

- 15 1. An oil well comprising a casing, a liquid eduction conduit arranged therein and having a liquid chamber embodying a sleeve which is such in diameter as to form a comparatively small gas space between itself and the casing, said sleeve being formed with a plurality of gas intake ports closed by valves, and packing arranged between the conduit and casing below said chamber to prevent the passage of gas downwardly 25 into the well to disturb the oil-sand.
- 20 2. A fluid conduit for use in connection with oil wells including an oil chamber formed from a comparatively short length of pipe connected to a relatively large sleeve, said pipe carrying a valve seat, a ball check valve co-operative with said seat, a stop arranged in said chamber and co-operative with said valve for limiting the 30 opening movement, said sleeve being formed with ports for passage of gases, and valves closing said ports.
- 25 3. An oil conduit having a chamber including a sleeve formed in its periphery

with a recess, a port communicating with said recess and the bore of said sleeve, a ring-nut partially closing the outer end of said recess, the inner side of said nut being formed with a valve seat, and a spring-pressed valve arranged in said recess and co-operative with said seat.

4. An oil well including a fluid discharge conduit composed of upper and lower telescopically connected sections, the upper section having a valved oil chamber, said chamber including means for forming a restricted gas space between itself and the well casing, and packing surrounding said upper section beneath said chamber and co-operative with the lower section for longitudinally compressing it when the weight of the upper section is exerted thereon.

5. In an oil well, an eduction conduit including upper and lower telescopically connected sections, said lower section embodying an anchor, said upper section having an oil chamber formed of a sleeve and a short length of pipe connected thereto, said sleeve being formed with gas intake ports, valves for normally closing said ports, said upper section also including a relatively long length of pipe connected to said first named pipe, a valve seat arranged between the adjacent ends of said pipes, a check valve co-operative with said seat, and packing surrounding said long length of pipe.

In testimony whereof we have hereunto set our hands.

JOHN N. HICKS.

CHARLES A. ELLIOTT.

PRICE DUNBAR.
